UNITED STATES PATENT OFFICE

JAMES M. SMITH, OF ORLAND, CALIFORNIA, ASSIGNOR OF ONE-HALF TO JOHN C. HAMILTON, OF BERKELEY, CALIFORNIA

MACHINE FOR RECOVERING PRECIOUS METALS

Application filed October 26, 1928. Serial No. 315,266.

This invention resides in the provision of a simple and inexpensive sampling machine with which gold, platinum and other precious metals may be recovered more quickly, 5 easily and thoroughly than by hand or other machine panning methods.

An object of the invention is to provide a machine of the character described which has a large capacity for handling ore and 10 by reason of its special construction and arrangement will yield a relatively great amount of precious metals in a comparatively short time without requiring undue effort on the part of the operator.

15 A further object is to provide a machine of the character described which will be small, compact and capable of being easily transported.

Another object is to provide in a machine 20 of the character described a novel, yet simple pan construction which together with the special means for agitating and reducing the dirt, provides for a quicker washing and panning action with a greater yield of precious metals than is possible under any other panning processes.

A still further object is to provide a machine of the character described with which gold and other precious metals may be easily 25 recovered from heavy gravel as well as from finer dirt without requiring undue exertion on the part of the operator.

Other objects and advantages will be apparent during the course of the following description.

In the accompanying drawings forming a part of this specification and in which like numerals are employed to designate like parts throughout the same,

30 Figure 1 is a top plan view of my device,

Figure 2 is a vertical sectional view taken through the center of the machine, shown in Figure 1,

35 Figure 3 is a fragmentary sectional view taken on the line 3—3 of Figure 1,

Figure 4 is a top plan view of a part of the operating mechanism of the machine,

40 Figure 5 is a vertical sectional view taken through the center of the machine, the operating mechanism and its associated parts

removed, and particularly showing the arrangement and construction of the pan,

Figure 6 is a sectional view taken on the line 6—6 of Figure 5,

45 Figure 7 is an enlarged sectional view taken on the line 7—7 of Figure 4, particularly showing the arrangement and construction of one of the agitating and rubbing members,

Figure 8 is a vertical sectional view taken 50 on the line 8—8 of Figure 7, and

Figure 9 is a sectional view taken on the line 9—9 of Figure 7.

In the accompanying drawings there is 55 illustrated one form of my invention in which the machine comprises pans 1 and 2 arranged in spaced superimposed relation one within the other and having spaced projections 3 on the pan 2 whereby the pan 1 is supported in spaced relation to the pan 2 for the most part and contacts with the pan 2 at the center portion thereof only. The pan 1 is provided centrally with a conical portion or member 4 and the remaining portion of the bottom 60

of the pan in flat annular form is provided with a series of spaced perforations or openings 5 whereby dirt and water may pass from pan 1 into pan 2. A heavy skeleton casting 6 is secured by a suitable fastening 7 to the base of the conical portion 4 and lies in close 65 engagement with the bottom of the pan 2. A suitable catch mechanism generally designated by 8 is employed to hold the pans 70 nested. Cooperating with this means is a combined handle and latch member 9 which assists in holding the pans nested in proper 75 relation. By this arrangement the pan 1 may be readily lifted from the pan 2 or placed in the pan 2 during the operation of the machine as will be later and more fully 80 described. The conical center portion 4 causes the dirt to work towards the perforated annular portion of the pan 1 during 85 the operation of the machine.

90 A special means made in accordance with this invention is provided for reducing the dirt and gravel in the pan 1 which means in this instance is hand operated so as to cause the agitating and rubbing members to move in a circular path in contact with the perforated 95 100

portion of the pan, which members will also rotate on their own axes while being given said orbital movement. Although in this instance it is operated by a crank, it may be power driven if desired. This special means 5 comprises a stud shaft 10 which is mounted in a tubular socket 11 carried by the casting 6 and projecting upwardly through the apex of the conical portion 4. The shaft 10 is fixed 10 against rotation and serves as a support for a large spur gear 12, which is fixed on the upper end of the shaft and lies above the cone parallel with the bottom of the pan. The upper end of the shaft 10 also serves as a support 15 for a rotatable circular frame, designated by the numeral 13, which frame carries a plurality of downwardly extending agitating and rubbing members designated by the numeral 14. In the present instance there 20 are three of these members arranged in a circular series and said members move in a circular path on rotation of said frame.

The frame 13 comprises an upper circular plate 15 and a similar lower plate 25 secured together by bolts 17 and nuts 18. The upper plate is provided with a central bearing 19 for the upper end of the shaft 10. A suitable bearing member 20 is provided at the central portion of the lower plate and 30 engages with a rounded portion 21 of the shaft 10. By this arrangement the plates 12 and 16 lie above and below the spur gear 12 with the result that the same may rotate freely on the shaft 10. At spaced points on their 35 peripheries said plates are extended considerably beyond the periphery of the spur gear in the form of ears 22 and the members 14 are carried by said ears. One of said ears, however, has an operating crank 23 fixed thereto 40 to whereby the frame 13 may be readily rotated.

The members 14 each comprises a vertical 45 rotary shaft 24 mounted in a suitable bearing 25, which depends from the underside of the lower plate 16. A pinion 26 is fixed to the upper end of the shaft 24 and meshes with the spur gear 12. By this arrangement the shafts 24 are rotated as the frame 13 is rotated, thereby causing the members 14 to rotate on their 50 own axes as well as to move in an orbital path. A suitable revolving lubricant cup 27 is carried by each shaft 24 and is arranged to prevent lubricant from running down into the pans. Suitably removably mounted on the 55 lower end of each shaft 24 is a circular flexible and compressible rubbing disc 28 preferably made of rubber and provided with notches 29 in its periphery. This disc is cupped and is in yielding contact with the perforated bottom 60 of the pan 1. It is held cupped by metal plates 29' fastened on the shaft 24 and functions to mash and reduce the dirt while it is rotating and moving orbitally in engagement with the bottom of the pan. Any dirt pressed 65 beneath said disc 28 will be mashed and forced

through the perforations. By this action the dirt and gravel is reduced to fine form and pushed through the perforated bottom of the upper pan into the lower pan. Agitating spurs 30 extend upwardly from said discs 28 and assist in agitating and in breaking up and reducing the ore or dirt. The reducing action of the disc is enhanced by the serrated or notched periphery.

The operation of my device is as follows:—

The dirt from which precious metals are recovered, is placed within the pan 1 and by any suitable means (not shown) the pan is continuously supplied with a suitable quantity of water. The operator then by means of the handle 23 rotates the frame 13 and causes the members 14 to move in a circular path as well as to rotate upon their own axes. This latter action is by reason of the pinions 26 meshing with the spur gear 12. The rubber discs 28 are moved and rotated while in yielding contact with the perforated bottom of the pan 1 and by this action of the said discs the dirt is broken up and reduced so that it will be forced through the perforations into the pan 2. Occasionally the frame 13 may be oscillated as well as rotated in order to quicken the dirt reducing action. The action of these members 14 is very much the same as the old rubbing action formerly used in the hand method, but of course it is more effective and thorough in the rubbing and washing action. The gold and other precious metals are collected in the bottom pan 2 and the tailings with the water will run out over the edge of the pan 2 thereby freeing the pan 2 of the great portion of the dirt during the concentrating operation. When the dirt has been washed from the pan 1 into the pan 2 said pan 1 is released and lifted from the pan 2 thereby making possible the final steps necessary to remove the gold or other precious metals from the bottom pan. This may be quickly done by pouring off the water and remaining dirt or tailings and following the methods usually practised in the hand operations of panning. By the use of this machine much of the drudgery engaged in hand panning methods is eliminated and a great yield of precious metals may be had with less effort than by hand methods.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a machine of the character described, comprising washing pans nested one within the other and being spaced from one another except at the central portions thereof where

the bottom of the uppermost pan engages with the bottom of the lowermost pan, said uppermost pan having perforations in the bottom thereof, a conical member projecting upwardly from the center of the uppermost pan, a rotatable frame mounted on the upper end of the conical member, a plurality of downwardly extending rotatable shafts carried by said rotatable frame, a gear fixed to said conical member, pinions on said shafts meshing with said gear and rubber discs fixed to the lower end of said shafts and yieldingly engaging the perforated portion of the upper pan.

2. In a machine of the character described, comprising washing pans nested one within the other and being spaced from one another except at the central portions thereof where the bottom of the uppermost pan engages with the bottom of the lowermost pan, said uppermost pan having perforations in the bottom thereof, a conical member projecting upwardly from the center of the uppermost pan, a rotatable frame mounted on the upper end of the conical member, a plurality of downwardly extending rotatable shafts carried by said rotatable frame, a gear fixed to said conical member, pinions on said shafts meshing with said gear and rubber discs fixed to the lower end of said shafts and yieldingly engaging the perforated portion of the upper pan, and a plurality of upwardly extending agitating spurs carried by said discs.

3. In a machine of the character described, comprising pans mounted one within the other and spaced apart except at the central portion thereof where the uppermost pan engages the bottom of the lowermost pan, means for detachably holding said pans thus assembled, a rotary member supported by and above the uppermost pan, a plurality of downwardly extending agitating members carried by the rotary member and having yielding contact at their lower ends with the bottom of the uppermost pan, the uppermost pan having perforations in the bottom thereof over which perforations said members travel, means for so moving said members, and means for causing said members to rotate on their own axes during the movement thereof relative to the pan.

In testimony whereof I affix my signature.
JAMES M. SMITH.
